Term of patent 14 years

(Cl. D81—10)

To all whom it may concern:

Be it known that we, Joseph M. Majewski, Jr., and Elton F. Whitfill, citizens of the United States, residing at Kansas City, in the county of Jackson and State of Missouri, have invented a new, original, and ornamental Design for a Broiler, of which the following is a specification, reference being had to the accompanying drawing, forming part thereof, in which

Fig. 1 is a perspective view of the top, back and one end of a broiler, showing our new design,

Fig. 2 is a slightly reduced front elevational view of the broiler shown in Fig. 1.

We claim:

The ornamental design for a broiler, substantially as shown.

JOSEPH M. MAJEWSKI, JR.
ELTON F. WHITFILL.
